UNITED STATES PATENT OFFICE.

HENRY HARRISON TURNER, OF NORTHFIELD, MINNESOTA.

CHAIR.

1,156,725.

Specification of Letters Patent.

Patented Oct. 12, 1915.

Application filed November 25, 1914. Serial No. 873,857.

To all whom it may concern:

Be it known that I, HENRY HARRISON TURNER, a citizen of the United States, and a resident of Northfield, in the county of 5 Rice and State of Minnesota, have invented a new and Improved Chair, of which the following is a full, clear, and exact description.

My invention relates to chairs of the reclining type.

The object thereof is to provide a simple, convenient, strong and inexpensive reclining chair which can be easily and quickly placed in any inclined position by the person occupying the chair, or transformed into a chair having a synchronized swinging back and leg support.

With the above and other objects in view, the nature of which will more fully appear 20 as the description proceeds, the invention consists in the novel construction, combination and arrangement of parts as herein fully described, illustrated and claimed.

In the accompanying drawings, forming 25 part of the application, similar characters of reference indicate corresponding parts in all the views, and Figure 1 is a side elevation of my invention; Fig. 2 is a fragmentary elevation of the chair partly in section showing the structure of the locking mechanism; Fig. 3 is a side elevation showing the back and leg support in a position transforming the chair into a Morris chair; Fig. 4 is a horizontal section on line 4—4, 35 Fig. 2; Fig. 5 is a plan view of the crank for the locking mechanism.

Referring to the drawings, 5 represents the seat frame, which may be provided, if desired, with a spring netting or a solid seat. 40 Rigid with the seat frame 5 are front and rear legs 6 and 7 respectively. The seat frame 5 with the legs 6 and 7 form the seat section, to which is hinged the back and leg support. The longitudinal members 8 of 45 the back portion of the chair are hinged to the sides of the seat frame 5 adjacent the rear legs 7. The longitudinal members 8 are hinged to said seat between their ends, with the lower curved end 9 of said longitudinal members extending below the seat frame 5.

Hinged to the seat frame 5 in front of the leg 6 is a leg support frame 10. The frame 10, forming the leg support, is connected to the frame of the back portion by

a sector 11 hinged with one end to the lower extremity of one of the longitudinal members 8. The other extremity of said sector is hinged to the frame 10. As shown, a yoke 12 is provided on the frame to facilitate the connection. 60

To maintain the back portion and the leg support fixed relatively to the seat section within the limit of the swinging movement of said back section and leg support, the sector 11 is provided with spaced notches 13. These notches come in register with a pin 14 carried by a yoke 15 which is pivoted to the leg 6. The engagement of the pin with the notches is controlled from one of the 65 arm supports 16, which are hinged to the longitudinal members 8 of the back portion, and to the seat frame 5 by stays 17. The control consists of a rod 18 connected to the pin 14 at one end and at the other end 70 to a crank 19 bearing in the side member of the seat frame 5. The crank 19 is connected by a rod 20 to a beam 21 mounted in the arm support 16. The free end of the beam 21 is close to the free extremity of 75 the arm support 16, so that the same can be easily operated with the fingers extending over the arm support. Normally the weight of the rod 18 and the yoke 15 tends to engage said pin 14 with any of the notches 80 coming in register with the pin. This tendency keeps the free end of the beam 21 away from the bottom of the arm support 16, and by moving said free end of said beam 21 toward the arm support, the pin 14 is disengaged from the notch of the sector 85 11, and, consequently, the back portion and the leg support are free to swing. By releasing the beam 21 the pin 14 will engage the first notch coming in register therewith, 90 when it is desired to have the back portion and the leg support free to swing, the pin 14 is disengaged from the sector 11 by maintaining the free end of the beam 21 against the bottom of the arm support 16 by a latch 95 22 provided on the under side of the arm support 16 where the beam 21 is provided. It will also be noted from the drawings 100 that all of the members forming the chair are of channeled iron, so as to give great rigidity and lightness to the structure; but it is understood that any other material of suitable shape and character can be used with the same result.

To form a better foot rest, the longitudi- 110

nal members of the leg support 10 are provided with a telescoping extension 23, which is normally maintained within the leg support 10 by coil springs 24, which anchors 5 said foot rest 23 to the leg support. When it is desired to use the leg support, the person occupying the chair engages the foot rest 23 with his foot and forces the same out; and the foot rest is maintained in the forced- 10 out position by the engagement of said foot rest with the feet of the person occupying the chair.

From the foregoing description, taken in connection with the accompanying drawings, the advantage of the construction and operation of the device shown will be readily understood by those skilled in the art to which the invention pertains, and while I have described the principle of operation, 15 together with the device which I now consider to be the best embodiment thereof, I desire to have it understood that the device shown is merely illustrative and that such changes may be made as are within the scope 20 of the appended claims.

Having thus described my invention, I claim as new and desire to secure by Letters Patent:

1. In a chair, a seat section, a back portion 30 mounted to swing on the rear part of said seat section, a leg support mounted to swing in the front of said seat section, a sector connecting the back portion to the leg support, said sector having spaced notches, 35 and means normally tending to engage said notches whereby said back portion and leg support may be locked to said seat section in different predetermined positions.

2. In a chair, a seat section, a back portion 40 mounted to swing in the rear of the said seat section, said back portion having a part thereof extending under the seat section, a leg support mounted to swing in the front of said seat section, a sector connecting the 45 part of the back portion extending below the seat to said leg support, said sector having

spaced notches, and locking means normally tending to engage a notch of said sector.

3. In a chair, a seat section, a back portion mounted to swing in the rear of the seat 50 section, a leg support mounted to swing in the front of said seat section, a sector connecting the back portion to the leg support, said sector having spaced notches, locking means normally tending to engage the 55 notches of said sector, means for placing said locking mechanism into inoperative position.

4. In a chair, a seat section, a back portion, a leg support, said back portion and 60 leg support being mounted to swing, a sector connecting the back portion to the leg support whereby said back portion and leg support swing in unison, an arm support connecting the back portion to the seat section, 65 and locking means adapted to engage the sector in predetermined places for locking the swinging movement of the back and foot rest.

5. In a chair, a seat section, a swinging 70 back portion, a leg support mounted to swing, means connecting the back portion to the leg support whereby the same are prevented from swinging, a crank, a rod connecting the crank to the lock, a lever associated with 80 one of the arm supports, a rod connecting said lever to the crank, and means associated with the lever for rendering the same inoperative.

In testimony whereof I have signed my 85 name to this specification in the presence of two subscribing witnesses.

HENRY HARRISON TURNER.
